UNITED STATES PATENT OFFICE.

ADELAIDE M. PORTER, OF GREENWICH, CONNECTICUT, ASSIGNOR TO HUYLER'S, OF NEW YORK, N. Y., A CORPORATION OF NEW YORK.

WRAPPED CANDY DOLL.

1,382,383.

Specification of Letters Patent. Patented June 21, 1921.

Application filed November 13, 1920. Serial No. 423,833.

To all whom it may concern:

Be it known that I, ADELAIDE M. PORTER, a citizen of the United States of America, residing at Greenwich, in the county of Fairfield and State of Connecticut, have invented new and useful Improvements in Wrapped Candy Dolls, of which the following is a specification.

This invention relates to a wrapped candy doll, the principal object being to wrap candy for selling purposes in a novel and attractive manner that will particularly appeal to children, and such that the wrapped candy may be played with as a doll until it is desired to eat the candy.

The invention consists in the construction, combination and arrangement of parts herein described and claimed, and illustrated in the drawings accompanying and forming part of this application.

The drawing shows a perspective elevation of a preferred embodiment of my invention, comprising a doll formed of wrapped pieces of candy.

Referring to the drawings, the body portion of the doll consists of one or more pieces of candy 1, which are preferably what are known as "hard candies," being approximately round in shape, wrapped in pieces 30 of paper 2, or other suitable material, of size large enough to envelop the candy, the edges of the paper being gathered together and twisted into tongue portions 3 arranged to be secured together preferably by cord or 35 paper twine 4 to hold the body forming candies in position.

The head is formed by a similar round hard candy 5, wrapped in similar manner by an enveloping paper 6 with the edges of 40 the paper twisted to form a tongue portion 7 which is bound with the tongue portions 3 of the body forming elements, preferably by the same cord 4.

The arms and legs are formed of stick 45 candies 8, 9, such as peppermint sticks, lemon sticks, and the like, wrapped in paper 10 twisted at each end of the sticks at one

end roughly representing hands 11 or feet 12, and at the other end forming tongue portions 13 arranged to be bound with the 50 tongue portions of the body and head members, preferably by the same cord 4.

The head portion is preferably decorated by painting on the paper thereof facial features as shown; and cotton or other substance 14 may be pasted on the top to represent hair, being of any desired color. In order to obtain different dressing effects, the paper used is preferably transparent, or semi-transparent, so that the colorings of 60 the candies show through, and by varying the type and color of the candies, different doll effects are produced.

The device remains useful as a doll until the cord 4 is removed, whereupon the component parts separate, the paper wrappings may be removed, and the candies are available for eating, being entirely uninjured or otherwise detrimentally affected by reason of the novel mode of wrapping.

Having now described my invention, I claim and desire to secure by Letters Patent:

1. A wrapped candy doll comprising substantially round candies wrapped and arranged to form body and head portions, and 75 candy sticks wrapped and secured to the body portion to form arms and legs.

2. A wrapped candy doll comprising hard and stick candies, paper wrapped around each candy and twisted, and means securing the twisted portions together, the stick candies arranged to represent arms and legs, and the remaining candies forming the body and head.

3. A wrapped candy doll comprising substantially round candies wrapped and arranged to form body and head portions, candy sticks wrapped and secured to the body portion to form arms and legs, and decorative matter on the head portion representing hair and facial features.

In testimony whereof I have signed my name to this specification.

ADELAIDE M. PORTER.
